UNITED STATES PATENT OFFICE.

ROBERT E. FRANKLIN, OF DUQUESNE, PENNSYLVANIA.

VALVE-CAP FOR HIGH-PRESSURE WELLS.

1,368,623.

Specification of Letters Patent. Patented Feb. 15, 1921.

Application filed May 26, 1920. Serial No. 384,487.

To all whom it may concern:

Be it known that I, ROBERT E. FRANKLIN, a citizen of the United States of America, residing at Duquesne, in the county of Allegheny and State of Pennsylvania, have invented new and useful Improvements in Valve-Caps for High-Pressure Wells, of which the following is a specification.

The object of the invention is to provide 10 a relatively simple and efficient means for capping and controlling the discharge from high pressure or spouting oil and gas wells as distinguished from those in which the material must be removed by a pumping 15 process, the construction of the capping means being such as to facilitate its application to the oil well tubing either prior to or during the discharge of the product therefrom, and to facilitate the control of the 20 flow of gas or oil after the capping operation has been effected; and with these objects in view the invention consists in a construction and a combination of parts of which a preferred embodiment is shown in the accompanying drawings wherein:

Figure 1 is a side view of the capping device applied in the operative position to a well tubing.

Fig. 2 is a similar view showing the first 30 step in applying the cap with the valved member thereof in its displayed relation to the securing member.

Fig. 3 is a sectional view of the device showing the parts in the positions which 35 they occupy just prior to the adjustment of the valved member to secure a tight joint between the lower extremity thereof and the terminal of the well tubing.

Fig. 4 is a sectional view showing the parts 40 in their operative relations with the valve open.

Figs. 5 and 6 are opposite side views at 45 right angles respectively to the plane of Fig. 1 to show the link and latch respectively in side elevation.

Fig. 7 is a transverse sectional view on the plane indicated by the line 7--7 of Fig. 1.

The cap consists essentially of a valved body member 10 having lateral outlets 11 50 communicating with coupling sleeves 12 for engagement by the adjacent extents of pipes for conveying the oil or gas to points of storage or use, the intermediary portion of the bore of the body member being reduced 55 to form a valve seat 13 in operative relation with which is arranged a valve 14 actuatable

by a stem 15 engaged by a hand nut 16; and an anchoring member 17 consisting in the construction illustrated of a split band adapted to encircle the well tubing 18 at a 60 point near its upper end and secured in clamping relation therewith by a bolt 19 engaging radial ears 20 on the extremities of the band, together with means for connecting the body member with the anchoring member to permit of the swinging movement of the former with relation to the latter in the operation of applying the cap to the well tubing.

As shown the connection between the body 70 and anchoring members consists of a link 21 pivoted as at 22 to the band forming the securing or anchoring member and attached at its upper end as at 23 to a ring 24 in which the tubular body of the cap is threaded as indicated at 25 to the end that the interval between the plane of the ring and the lower extremity of the body member may be adjusted to suit the position of the anchoring member or clamp 17 on the end 75 of the well tubing. At its lower end the body member is provided with an enlargement or sleeve 26 shouldered internally as indicated at 27 to bear upon the upper edge of the well tubing, the lower portion of the 80 sleeve fitting down over the exterior surface of the portion of the well tubing extending above the plane of the upper edge of the band 17, so as to bear substantially and effectively upon said tubing when the parts 85 are relatively adjusted for operation as indicated in Fig. 4.

At the opposite side of the structure from the loose or swinging link 21, which permits the movement of the body member of the 90 cap relative to the fastening or anchoring member formed by the clamping band in the operation of applying the device to the well tubing, there is located a yielding latch 28 consisting of a spring tongue secured at its 95 upper end to the ring 24 and shouldered at its lower extremity as indicated at 29 for engagement with a seat 30 formed in a catch 31 permanently secured to the exterior surface of the wall of the band 17.

In the application of the device to the well tubing the parts being substantially in the position indicated in Fig. 2, the band 17 is placed around the tubing and adjusted by means of the bolt 19 to engage the same 100 firmly, after which the body member of the cap is swung upward into alignment with

the tubing to occupy the position indicated in Fig. 3 and the latch 28 is snapped into engagement with the catch 31, after which the tubular body member of the cap may be 5 screwed downward through the ring 24 to place the link 21 and latch 28 under tension and secure a firm and fluid tight joint between the lower end of the body member and the upper extremity of the well tubing.

10 The adjustment of the valve 14 will then provide for the control of the discharge from the well as may be desired by the operator.

Obviously the removal of the cap from the 15 well may be as readily effected by a reversal of the steps herein above specified, and the cap is therefore applicable successively to a plurality of wells as the output therefrom may require, no material modification in the 20 construction of either the tubing or the cap being necessary in connection with such successive applications.

What is claimed is:

1. A capping device for high pressure oil 25 well tubing having a body member provided with a valved outlet, an anchoring or fastening member for engagement with the well tubing, and flexible connections between said members to permit of the swinging 30 movement of the former with relation to the latter.

2. A capping device for high pressure oil well tubing having a body member provided with a valved outlet, an anchoring or fastening 35 member consisting of an adjustable clamping band for engagement with the well tubing adjacent to its upper end, a link connecting said body member and band to permit of swinging movement of the former 40 relative to the latter, and means for holding said members in aligned relations.

3. A capping device for high pressure oil well tubing having a body member provided with a valved outlet, an anchoring member 45 for engagement with the well tubing, and tensile connections between the body member and the anchoring member, the body member having a threaded engagement with said tensile connections.

50 4. A capping device for high pressure oil well tubing having a tubular body member

provided with a valved outlet, an anchor band for engagement with the well tubing, and a ring movably connected with said anchoring member and adapted for registration with the tubing engaged by the latter, the tubular body member being threaded in said ring.

5. A capping device for high pressure oil well tubing having a tubular body member 60 provided with a valved outlet, an anchoring member consisting of a contractile clamping band for engaging the well tubing, a ring having a link connection with said anchoring member and a latch for securing 65 the ring in axial alinement with the anchoring member, the body member being threaded in said ring for terminal contact with the extremity of the well tubing.

6. A capping device for high pressure oil 70 well tubing having a tubular body member provided with a valved outlet, an anchoring member consisting of a contractile clamping band for engaging the well tubing, a ring having a link connection with 75 said anchoring member and a latch for securing the ring in axial alinement with the anchoring member, the body member being threaded in said ring for terminal contact with the extremity of the well tubing and 80 provided with an exterior sleeve for embracing the upper extremity of said tubing.

7. A capping device for high pressure oil well tubing having a tubular body member provided with a valved outlet, an anchoring 85 member consisting of a contractile clamp for engagement with the well tubing, a ring loosely connected with the anchoring member by an interposed link, and a latch member carried by the ring for engagement with 90 a catch on the anchoring member to retain the ring in axial alinement with the anchoring member, the body member being threaded in said ring for axial adjustment relative thereto and provided at its lower end with a 95 sleeve for embracing the upper end of the well tubing, said sleeve having an internal shoulder for bearing contact with the extremity of the tubing.

In testimony whereof I affix my signature. 100

ROBERT E. FRANKLIN.
